United States Patent

Des. 238,375

Patented Jan. 6, 1976

238,375

WALKIE TALKIE

Kenneth R. Wilkes, Marcellus, N.Y., assignor to
General Electric Company, Syracuse, N.Y.

Filed June 4, 1974, Ser. No. 476,205

Term of patent 14 years

Int. Cl. D14—03

U.S. Cl. D26—14 K

FIG.1

FIG.2

FIG.3

FIG.4

FIG. 1 is a front elevational view of a walkie talkie showing my new design;

FIG. 2 is a rear elevational view thereof;

FIG. 3 is a top plan view thereof;

FIG. 4 is a bottom plan view thereof;

FIG. 5 is a right side elevational view thereof; and

FIG. 6 is a left side elevational view thereof.

I claim:

The ornamental design for a walkie talkie, as shown.
